N. PETERS, Photo-Lithographer, Washington, D. C.

UNITED STATES PATENT OFFICE.

HENRY F. STAUS, OF CHESTER, PENNSYLVANIA.

ELECTRIC MAIL-BOX AND INDICATOR.

SPECIFICATION forming part of Letters Patent No. 337,796, dated March 9, 1886.

Application filed October 29, 1885. Serial No. 181,230. (No model.)

To all whom it may concern:

Be it known that I, HENRY F. STAUS, a citizen of the United States, residing at Chester, in the county of Delaware and State of Pennsylvania, have invented certain new and useful Improvements in Electric Mail-Boxes and Indicators, of which the following is a full, clear, and exact description, reference being had to the accompanying drawings, forming a part of this specification.

My invention relates to apparatus for signaling from a mail-receiving box to a point in the building where such box is located when a letter is deposited in such box, and for indicating when the owner of the box is within or without the building; and it consists in a mail box or receptacle containing three revolving contact-buttons of similar construction operated by a removable key, with an indicator operated by two pairs of magnets controlled by the two lower revolving buttons, and a series of circuit-wires leading thereto from the source of electric supply.

It also consists in an electric call-bell electrically connected with a pair of electric batteries, and with the third revolving contact-button contained and supported within the mail-box, and a series of necessary circuit-wires for producing such electrical connection.

In the accompanying drawings, in which similar letters of reference denote like parts in the several views, Figure 1 is a front elevation of the complete apparatus, (the lower part of the box being partly broken away to show the indicator mechanism,) showing the mail-box with its apertures for the reception of letters and for disclosing the indicator-arm, the pair of batteries, the call-bell, the location and arrangement of the circuit-wires leading to and from the several revolving buttons contained in the box. Fig. 2 is a front elevation of the indicator mechanism. Fig. 3 is a side view of the mail-box and contact-buttons. Fig. 4 is a plan view of the top part of the lower section of one of the revolving buttons, and Fig. 5 a view of the under side of the upper section. Fig. 9 is a plan view of the top of the said upper or outside section of one of the buttons, and Fig. 7 is a vertical cross-section of the complete revolving

circuit-closing button with the key inserted therein. Fig. 8 is a front elevation of the key, and Fig. 6 an end view thereof from the bottom.

The mail box or receptacle M is of any convenient form, preferably rectangular, of sufficient height, width, and depth to contain the mechanism hereinafter described, and having an aperture, F, in its front side, through which letters may be dropped into the box, and having also an inner perforated partition, G, on which such letters fall, and a door or other opening located between said aperture F and partition G. At a convenient place in the box, preferably the top above the aperture, is located the upper revolving contact-button, E, the lower section of the button being within the box, and the upper section protruding beyond the surface of the outside face of the box. At the base of the mail-box, below the partition G, two round or square holes, L and O, are cut, and on the inner side of the box opposite these holes are painted or otherwise displayed the words "In" 75 "Out," and below these, inside the box, is located the indicator mechanism, consisting of two of said revolving contact-buttons, A and B, connected by circuit-wires with two pairs of magnets, C and D, the button A controlling one magnet and the button B controlling the other magnet, as hereinafter more particularly described.

The location, connection, and arrangement of the circuit-wires are as follows: Between the pair of electric batteries 1 and 2 a connecting-wire, 4, for the opposite pole, is used, and from battery 1 a wire, 5, leads to the button E, being connected with one of the bars 26, Fig. 4, therein, and also to one of the bars in the button A, as shown in dotted lines in Fig. 1. A wire, 3, leads from battery 2 to the bell. Wire 6 leads from the bell to the button E, connecting with the opposite bar therein from that to which wire 5 is connected. 95 Wire 7 leads from battery 2 (the same pole of the battery to which the bell is connected by wire 3, producing reverse current) direct to wire 17, which connects opposite bars of the two lower buttons which control the two pairs of magnets C and D. Wires 15 and 16, Fig. 2, connect with revolving contact-buttons A

and B on right and left sides, respectively, of magnets C and D. Wire 18 leads from post 12 to wire 5 by looping therewith.

- The revolving contact-buttons A, B, and E are all constructed alike. They are made in two sections or halves, as shown together in Fig. 7, and when adjusted relatively to each other, as shown in said figure, are held together by screws *a a*, or other suitable means.
- 10 The top section, K, is an annular block of suitable material recessed from beneath to admit of the reception in such recess of the lower section, J. In the center of said section K a central hole, 32, is cut to admit the middle prong, 19, of the key S, and in a diametrical line with said hole 32 two other holes, 23 and 24, equidistant therefrom, are cut to admit the outer prongs, 20 and 21, of the said key. A slot or slots, 30 and 31, of circular form in 20 length, are cut in the surface of said top section and terminate in said holes 23 and 24. The under side of said upper section is shown in Fig. 5. It is provided with a bar, 22, capable of being moved in the arc of a circle, 25 and provided with a central hole in line with the hole 32, and of the shape of the prong 19 of the key. In its normal position the ends of this bar cover the under side of the holes 23 and 24. The under section or half of the 30 contact-button is an annular non-conducting plate, preferably provided with a central hole or slot, 33, to receive the end of the prong 19 and steady the key, and having two metal bars, 25 and 26, to opposite ends of which are 35 attached the circuit-wires. The key S is shown in Figs. 6 and 8, its characteristics being three prongs, two, 20 and 21, being of equal length and of form to correspond with the slots and side holes in the button, and the center prong, 19, being of greater length and of such shape that it will revolve the bar 22 when inserted within the same. It is thus seen that different keys can be made for different buttons on different boxes.
- 40 The operation is as follows: The prong 19 is inserted in the top center hole, 32, of the button, which causes the prongs 20 and 21 to enter the slots 30 and 31, and the key is then turned until the bar 22, which in normal position covers the under side of the holes 23 and 24 has moved around and uncovered these holes, which is at the same time that the outer prongs, 20 and 21, of the key have reached the outer holes, 23 and 24, at the ends of the 45 slots, which thus leaves a free passage-way for the penetration of all three prongs of the key through the top section of the button, and in consequence the center prong enters the steady or guiding slot 33, and the outer 50 prongs touch the contact-bars 25 and 26, thus completing the electric circuit between them and the circuit-wires attached thereto through the key S by its outside prongs, 20 and 21.

The bell R is of the usual and well-known construction of electric call-bell, and need not be here more particularly described, nor the batteries 1 and 2, they being of the usual and

well-known kind ordinarily used for like purposes.

The indicator mechanism consists of two pairs of magnets, C and D, (arranged as shown in Fig. 2,) wound with soft wire, and supported longitudinally in two supporting posts arising from a base-support, from which latter arises a center post, 10, on which is pivoted at the base an armature, N. At the upper extremity of the post 10 is pivoted a needle, H, carrying at its end a card, or having an enlarged end, so that when swinging from side to side its end will cover and uncover alternately the holes L and O on the outer surface of the mail-box. This needle is of peculiar conformation in that it terminates in two prongs, forming a triangle or a crescent, in order that when armature N is drawn toward its attracting-magnet it will strike such prong with certainty. The action of this mechanism is as follows: When the key S is inserted in the button B and the latter is revolved thereby, as above described, the outer prongs of the key will reach the contact-bars 25 and 26, closing the circuit, which has the effect of drawing the armature N to the magnets D, thus shifting the needle H. A similar insertion of the key S in the opposite button, A, draws armature N to magnets C, and thus moves the needle in the opposite direction.

I am aware that an electric mail-box has been used in which the dropping of a letter or card on an inclosed platform in the box 100 closes the electric circuit and rings a call-bell; but the great disadvantage of such a device is that the bell is kept constantly ringing until the circuit is broken by withdrawal of the card or letter, and such boxes being liable to 105 be filled with letters, cards, circulars, advertisements, &c., this objection is so great as to make the apparatus exceedingly undesirable. With my device the platform is a mere receptacle for the letter, the circuit being closed 110 only by the postman or some one possessing the key. It has the additional advantage of being a calling or signaling instrument from one part of the building to another, and also, further, of electrically indicating or registering whether the proprietor or owner of the 115 box is within or without the building, and so informing depositors of letters or callers, and it is apparent that different forms of keys can be made for different boxes.

Having thus described my invention, what I claim as new, and desire to secure by Letters Patent, is—

1. An electric signal and letter box composed of the receptacle M, call-bell R, an electric battery, a series of circuit-wires, and circuit-closing mechanism consisting of the revolving circuit-closing button E, constructed substantially as described, and a removable key, S, having two contact-prongs and a guiding-prong adapted to fit in said button and revolve the same, as set forth.

2. The combination, with the receptacle M, constructed, as described, with openings, L and

O, circuit-closing mechanisms, and electric battery, and series of circuit-wires, of indicator mechanism consisting of a pair of right-hand magnets, D, and a pair of left-hand magnets, C, 5 armature N, supporting post 10, and needle H, substantially as described.

3. Circuit-closing mechanism consisting of the upper and lower sections, K and J, the latter having metallic contact-bars 25 and 26, 10 to which the opposite wires of an electric circuit are respectively connected, and the former provided with a central vertical opening, 32, and with vertical openings 23 and 24 at the termini of circular slots 30 and 31 circumferentially surrounding, said central opening, 15 said upper section, K, being also provided on its under side with a rotating pivoted bar, 22, having a central vertical opening of irregular shape corresponding in position with said central opening, 32, said mechanism being constructed, combined, and operating substantially as set forth.

4. Circuit - closing mechanism constructed

substantially as described, in combination with a key, S, having a central prong, and 25 also two side prongs of equal length, but the former being of greater length than the two latter and corresponding in form with the central opening in the pivoted bar 22 of said circuit - closing mechanism, and said side 30 prongs being adapted to fit said slots and recesses 23 and 24, whereby on the insertion of said key in the vertical opening of the pivoted bar 22 and the rotation of the same thereby said outside prongs will penetrate to 35 the surface of the contact-bars 25 and 26 and complete an electric circuit, substantially as described.

In testimony whereof I have hereunto affixed my signature this 3d day of October, A. D. 40 1885.

HENRY F. STAUS.
